UNITED STATES PATENT OFFICE.

JOHN T. STORTZ AND HARRY L. STORTZ, OF PHILADELPHIA,
PENNSYLVANIA.

DESIGN FOR A WRENCH AND SCREW-DRIVER.

SPECIFICATION forming part of Design No. 28,380, dated March 15, 1898.

Application filed July 8, 1897. Serial No. 643,907. Term of patent 7 years.

all whom it may concern: We, JOHN T. STORTZ and HARRY L. STORTZ, citizens of the United States, residing at Philadelphia, Pennsylvania, have invented and produced a new and useful Design for a Wrench and Screw-driver, of which the following is a specification, reference being had to the accompanying drawing, forming part thereof. The drawing is a perspective view showing the new design. As shown in the drawing, the leading or serial feature of the design consists of a piece of metal, one end of which is the widest and has the general curved outline of an oval shape, the top or extreme end being round and having in the outer or circumferential edge of said wide part apertures, jaws or openings, and slots of various sizes cut through at right angles to the face or surface of the metal, as shown at B E F G H; also, holes or openings of various sizes of hexagonal and square shape cut through the inside or within the edge of the aforesaid wide part, as shown in drawing at

The other end of the metal or handle of the wrench is elongated and has the shape of

a screw-driver blade, the wide part being formed in shape to answer as handle to the elongated end, and vice versa.

The letters A and K show the shape of the concaved curve of the edge connecting the elongated part with the wide part and forming with a slightly-extended end of the edge of the wide part a point of a spanner.

It is manifest that the design embraces in a wrench and screw-driver the general shape of an elongated end or blade and a wide end, the general outline of which would be a curved or oval shape with apertures, slots, jaws, or openings of various sizes cut in the outer edge thereof, all substantially as shown in the accompanying drawing.

Having described our invention, what we claim as new, and desire to secure by Letters Patent, is—

The design of a wrench and screw-driver as herewith described and shown.

JOHN T. STORTZ.
HARRY L. STORTZ.
